UNITED STATES PATENT OFFICE.

SHERMAN L. DAVIS, OF BLOOMINGTON, INDIANA.

HYDROCARBON-BURNER.

954,380.

Specification of Letters Patent.

Patented Apr. 5, 1910.

Application filed October 26, 1907. Serial No. 399,359.

To all whom it may concern:

Be it known that I, SHERMAN L. DAVIS, a citizen of the United States, residing at Bloomington, in the county of Monroe, State of Indiana, have invented certain new and useful Improvements in Hydrocarbon-Burners, of which the following is a description, reference being had to the accompanying drawing, and to the numerals of reference marked thereon.

My invention relates to vapor burners and more especially to devices for vaporizing and burning heavy hydro-carbon oils such as kerosene, although it will be obvious that from certain aspects, my improved burner may be used with vapors of any character.

The object of my invention is to provide a burner wherein heavy hydrocarbon oils may be gradually heated and vaporized, and then intimately mixed with air and burned.

A further object of my invention is to provide a burner wherein the pipes conveying the heavy oil are so related to the burner that the oil is gradually heated and then suddenly vaporized in a short hot zone of the delivering pipe from which the vaporized oil will pass rapidly to the burner, leaving little or no deposit of carbon in the delivery tubes and the valve of the burner.

A further object of my invention is to provide a burner having a valve and ports for the intaking of air, so related that the valve will throw a film of vapor across the path of the air entering said ports.

A further object of my invention is to provide a delivering pipe which is so positioned in the burner that the path of movement of the oil or vapor therethrough is continuously in a downward direction and wherein said pipe may be also readily blown out to free the same from carbon deposits therein.

Further objects of my invention will in part be obvious and will in part be herein-after more fully explained.

In the drawings which show by way of illustration one embodiment of my invention:—Figure 1 is a view in side elevation, with certain parts sectioned showing my improved burner, the support therefor and the storage tanks and delivery pipes for the oil. Fig. 2 is a sectional view through the burner. Fig. 3 is a detail in bottom plan of the movable collar for closing the air ports. Fig. 4

is a sectional view showing the connection of the delivering pipe to the valve stem of the burner. Fig. 5 is a detail showing the manner of attaching the supply pipe to the distributor.

In carrying out my invention, I preferably use a tank 1, which is closed at the top and has an inlet opening 2, which may be closed by any suitable means. Within the tank 1 is a second auxiliary tank 3 which may be filled through a short tube 4 secured to the top of the main tank 1, and closed by a suitable cap 5.

The pipe 6 is led through the top of the tank 1, and extends down into the auxiliary tank 3 to a position closely adjacent the bottom thereof. The pipe 7 extends through the closed top of the tank 1 and extends to a position closely adjacent the bottom of the main tank 1. The pipes 6 and 7 are connected to a single delivery pipe 8, which leads to the burner. The valve 9 of any suitable construction is located in the pipe 6, and controls the flow of the oil from the pipe 6 into the pipe 8. The valve 10 which is also of any suitable construction, controls the flow of oil through the pipe 7 into the pipe 8. I have also provided a short pipe 11 which is suitably secured to the top of the main tank 1, and which carries at the upper end, a pressure gage 12. Said pipe 11 is connected to a pipe 13 which is provided with a valve 14 of any suitable character.

The purpose of the pipe 13 is for the connection of a pressure pump so that the main tank 1 and also the auxiliary tank 3 which opens at the top into the main tank 1, may be put under suitable air pressure for delivering the oils from said tank.

My improved burner consists of a distributor 15 where the vapors are ignited, a mixer 16, where said vapors are intimately mixed with air, and a valve 17 which controls the flow of the vapor into the mixer. Said distributor 15 is preferably cylindrical in shape and has its upper end closed as clearly shown in Fig. 2. The distributor 15 is provided with an outwardly extending ledge 18, at its lower end, and a downwardly extending tapered neck portion 19, which closely fits the upper cylindrical portion 20 of the mixer. The outwardly extending ledge 18 is provided with a recess or depression 21 in which preferably denatured alco-

hol may be placed and ignited for the purpose of warming up the distributer and the delivery pipes encircling the same.

The mixer as shown in the present embodiment of my invention, is made of the frusta of two cones placed base to base and secured together. The lower cone shaped portion of the mixer is provided with inlet air ports 23. Said lower portion of the mixer is provided with a rotatable cone-shaped member 24, conforming in shape to the lower portion of the mixer and held thereon by an adjustable nut 25. By adjusting the nut 25, the cone-shaped member 24 may be brought into proper position relative to the lower portion of the mixer. Said cone-shaped member 24 is provided with ports 26 of practically the same size as the ports 23 in the mixer. Said member is also provided with a suitable handle 27 whereby said cone-shaped member may be rotated to close the ports in the mixer, more or less as desired. Said mixer as above noted, is provided at its upper end with a cylindrical extension forming a shoulder 28, which serves as a seat for the distributer and said cylindrical portion of the mixer extends a slight distance into the distributer. The lower portion of the mixer is screw threaded as at 29, and said screw threaded portion engages the screw threaded portion on the outer surface of the valve 17.

The valve 17 is screw threaded at its lower end and to said screw threaded portion is secured a cup 30 into which denatured alcohol may be poured and ignited for the purpose of warming up the valve 17 when the burner is to be started. The valve 17 is tubular in form and has at its end, a closing wall 31 which is provided with a tapered opening 32 through which the vapor passes into the mixer. The inner member 33 of the valve is threaded to engage a screw thread 34, formed on the interior surface of the valve 17. Said inner member extends upward into said valve, and is so shaped as to be spaced a slight distance from the inner wall of the valve. Said inner member is tapered at its upper end in substantially the same form as the inner tapered surface of the outer member of the valve 17 at its end.

The delivery pipe 8 is coiled about the distributer 15 and the first coil 35 is secured to the distributer by any suitable means, such as by riveting, as shown in Fig. 5. The second coil 36 is however, slightly spaced from the distributer, while the third coil 37, is spaced a considerable distance from the distributer.

It will be noted that the delivery pipe 8 as it passes about the distributer, extends continuously downward and the drop in the pipe for each coil, is preferably equal to at least twice the diameter of the pipe. Said distributer is provided with a series of perforations 38 which extend about the distribu-

ter substantially in the same direction as the delivery pipe. Said perforations or openings 38 are located at some distance below the coils 35 and 36. Said perforations are also located directly in the rear of from one-half to two-thirds of the length of the lower coil 37, so that said portion of the coil 37 will lie directly in the apexes of the flame jets, issuing through the perforations 38 in the distributer. It will thus be seen that as the oil passes along the delivery pipe, it will be heated in the coils 35 and 36 but not sufficiently hot to raise the oil to the vaporizing point. As soon as however, the oil passes into the coil 37, which is located directly in the apices of the flame jets, said oil will be vaporized and the vapor will be driven forward very quickly into the supply valve and thence into the mixer and to the distributer. If all the heating coils of the pipe were located in the apices of the flame jets, the oil would be dissociated into light gases such as marsh gas, and would consequently be attended with the separation of much carbon within the pipe, thereby closing up said pipe. By my improved burner, however, wherein the oil is only heated but not vaporized in the first portion of the heating coils and is vaporized in a short hot zone, I avoid the deposition of carbon in the heating tube.

It will also be noted that the heating coils as they pass about the distributer extend continuously in a downward direction, so that the free flow of oil and vapor is in no wise retarded. The delivery pipe 8 after being coiled about the distributer extends downward into a coupling 39. Said delivery pipe extends well into said coupling and a suitable packing nut 40 prevents the escape of the vapors from said coupling. Said coupling is secured at its opposite end to a short delivering pipe 41 which is formed integral with the valve of the burner as clearly shown in Fig. 4. An opening 42 connects the short delivery pipe 41 with the valve 17. The short delivery pipe extends beyond the valve stem and is provided with a closing cap 43.

Any free carbon which may enter the short length of the delivery pipe is usually driven into the extended end thereof which acts as a reservoir for the same. By removing the cap, the short delivery pipe is opened and may be readily cleaned of any obstruction. The inner member 33 of the valve extends to a considerable distance beyond the outer end of the outer valve member 17 and is provided with a hand wheel 44 by means of which said inner member relative to the outer member, may be adjusted. When the inner member of the valve is turned in, the passageway between the upper free end of said inner member and the upper inner face of the outer member is made smaller, thus cutting off the supply of vapor. On the

other hand, when the inner member is turned outward, this passage is enlarged and the supply of vapor increased.

I have preferably made the inner member 5 of my valve tubular in form and provided the same with a needle 45. Said needle 45 is screwed into a tapered shank portion 46 shaped to fit a tapered seat 47 in the member 33. Said tapered shank portion therefore, when on the seat 47, serves as a closing valve to prevent any of the vapors from passing out through the hollow inner member. Said needle is provided with an outwardly extending stem 48 which extends 10 into a thumb piece 49 and is secured thereto by a pin 50. The outer end of the inner member 33 is slotted at 51 to receive the projecting pin 50 so that said needle stem carrying the needle may be reciprocated within 15 the inner member 33. When the needle is withdrawn into the inner member 33, the pin 50 engages the outer cam surface 52 of the member 33 and by turning said needle and stem through the thumb piece 49, the 20 tapered shank 46 is drawn firmly on to its seat. When the needle is pushed forward the point thereof enters the outlet opening in the head of the valve, and any particles of carbon or the like which may have lodged 25 in said opening, may be readily removed.

Before starting the burner, the needle is forced forward to clear the opening in the valve after which it is retracted and the shank portion 46 drawn down firmly on its seat. The cup 30 is preferably threaded 30 into a supporting stand 53 or the like.

The manner of operation is as follows:— The main tank 1 is partly filled with kerosene or some other heavy hydrocarbon oil 40 and the auxiliary tank 3, is partly filled with gasolene which may be poured into the same through the short tube 4. After the tanks have been filled, the screw caps 2 and 5 are tightened closing the tank to the outer air. 45 A pressure pump is now attached to the short length of pipe 13 and the air above the oil and gasolene is put under pressure. When the pressure gage indicates the desired pressure, the valve 14 is closed. Denatured alcohol is now poured into the cup 30 and ignited. When said alcohol is nearly burned 50 out, a small quantity of alcohol is placed in the annular depression or recess 21 and ignited. This warms up the coils about the 55 distributor. When the alcohol in the cup 30 and the depression or recess 21 is completely burned, the valve 9 is opened slightly to admit a small stream of gasolene. This gasolene is instantly vaporized in the hot 60 coils and the hot short delivery pipe 41 and valve 17 and issues therefrom into the mixer in the form of vapor and finally into the distributor, where it is ignited in the usual manner. The flames which issue from the 65 openings 38, raise the coils encircling the

distributor to a high temperature in a very short time. When the desired temperature is secured in said coils, the valve 10 is opened which admits a heavy oil, and the valve 9 is closed shutting off the gasolene. 70 The heavy oil on reaching the hot coils is first heated nearly to the point of vaporization, and as it reaches the short hot zone, in the coil of pipe lying directly in the apices of the flames, said oil is vaporized 75 and is pushed forward quickly into the valve issuing therefrom in the form of a gaseous vapor practically in the same manner as gasolene. The inlet air ports allow the air to pass in and to become thoroughly 80 mixed with the oil vapor. A little more air is of course required when the oil is turned on. The flame made by the burning oil is very hot and blue, odorless, and free from unburned carbon.

Owing to the shape of the outlet opening in the valve 17, and the inner member 33, which is located at a point closely adjacent the outlet opening, the vapor leaves said opening in the form of an inverted cone (see dotted line, Fig. 2), striking against the walls of the upper portion of the mixer substantially at the points α , α . The vapor is from this point deflected across and upward until it strikes again, the walls of the mixer. 90 By this throwing of the vapor against the wall of the mixer, it will be seen that said vapor is thrown entirely across the path of the air passing into the mixer, so that the air passing up through the mixer must necessarily be intimately mixed with the oil vapors. 100

When it is desired to extinguish the flame, the valve 9 is opened to admit the gasolene and the valve 10 is closed. This substitution of the gasolene for the oil in the delivery pipe 8 frees the pipe and coils and the valve of any heavy oil vapor which would condense on cooling and making the burner difficult to start, when it is desired to use the same again. The sudden vaporization of the gasolene, increases the gas pressure in the coils and the valve, which blows out any particles of free carbon, making the burner 110 practically self-cleaning.

As a means for screwing the inner member 33 into the valve 17, I have provided a wheel 44, which is preferably threaded onto the member 33 and secured in any desired position by a suitable set screw. When the inner member 33 is screwed in to its normal operating position, the hub of the wheel 44, as shown in Fig. 2, contacts with the outer end of the valve 17 and a suitable leaded bearing or washer may be provided which will assist in making a gas tight fitting at the lower end of the valve. 120

When it is desired to adjust the position of the inner member 33 relative to the outer member 17 of the valve, the set screw is 130

loosened and the position of the hand wheel 44 relative to the inner member 33, adjusted. By this means, I have provided a simple device for holding the member 33 in its adjusted positions and have also provided a suitable means whereby said inner member 33 may be readily removed for cleaning.

Having thus particularly described my invention, what I claim as new and desire 10 to secure by Letters Patent is:—

1. A hydrocarbon burner including in combination, a distributer where the vapor is ignited, a delivery pipe for said vapor coiled spirally in a downward direction about said distributer, said distributer having openings therein arranged in a spiral row, said spiral row of openings at the upper end of the distributer being arranged below said pipe, and at the lower end of said 20 distributer being arranged directly opposite said pipe, whereby the oil in said pipe is heated first gradually and finally quickly vaporized in a short hot zone of said pipe.

2. A hydrocarbon burner including in combination, a distributer where the vapor is ignited, a delivery pipe for said vapor coiled spirally in a downward direction about said distributer, said distributer having openings therein arranged in a spiral row, the first coil in said delivery pipe being located close to said distributer and each succeeding coil being spaced farther from the distributer than the preceding coil.

3. A hydrocarbon burner including in combination, a distributer, where the vapor is ignited, a delivery pipe for said vapor coiled spirally in a downward direction about said distributer, said distributer having openings therein arranged in a single spiral, the first coil in said delivery pipe being in contact with the distributer, and the succeeding coils being spaced therefrom.

4. A hydrocarbon burner including in combination, a distributer where the vapor is ignited, a delivery pipe for said vapor coiled spirally in a downward direction about said distributer, said distributer having openings therein arranged in a single spiral, the first coil in said delivery pipe being in contact with the distributer and the succeeding coils spaced therefrom, with a portion of the last coil located directly in front of the openings in the distributer, whereby a hot short zone is formed for 55 quickly vaporizing the oil.

5. A hydrocarbon burner including in combination, a distributer, having openings where the vapor is ignited, a delivery pipe coiled about said distributer, the first coil in 60 said delivery pipe being located outside of and in contact with said distributer, and each succeeding coil being spaced farther from the distributer than the preceding coil, with a portion of the last coil located directly in front of the openings in said dis-

tributer, whereby a hot short zone is formed for quickly vaporizing the oil.

6. A hydrocarbon burner including in combination a distributer, having a series of openings therein arranged in a spiral row where the vapor is ignited, a delivery pipe coiled exteriorly about said distributer, the first coil thereof being located above said openings, and attached to the distributer, the second coil being spaced from said distributer slightly, and located above a portion of said openings, and the third coil being spaced still farther from the distributer and having a portion thereof located directly in front of another portion of said openings, whereby a portion of said last coil will lie directly in the apices of the flame jets.

7. A hydrocarbon burner including in combination a distributer having openings where the vapor is ignited, a supply valve for the distributer, and a delivery pipe having coils extending exteriorly about said distributer, the upper coil being in contact with said distributer, and the lower coil being spaced farther from the distributer than the preceding coil and having a portion thereof located directly in front of the openings in said distributer, said delivery pipe extending about said distributer in a downward direction and having connection with the supply valve.

8. A hydrocarbon burner including in combination, a mixer, a distributer, detachably connected to said mixer and located above the same, a supply valve for said mixer, a delivery pipe extending about said distributer and to said valve continuously in a downward direction, said distributer having a spiral row of perforations arranged adjacent to said delivery pipe.

9. A hydrocarbon burner including in combination, a distributer, a mixing chamber comprising two members in the form of the frusta of two cones having straight walls and arranged base to base, a supply valve having a single delivering opening located in the axis of said cones and at the base of the lower cone, said valve having means, whereby a widely spread cone of vapor is thrown against the central portion of the inclined walls of the upper cone-shaped member of the mixing chamber, said upper cone-shaped member having an unobstructed extension leading to said distributer, and air 120 ports in said mixing chamber below the points where the vapor strikes the same.

10. A hydrocarbon burner including in combination, a distributer, a mixing chamber comprising two members in the form of the frusta of two cones having straight walls and arranged base to base, a supply valve having a single delivering opening located in the axis of said cones and at the base of the lower cone, said valve having means 130

- whereby a widely spread cone of vapor is thrown against the central portion of the inclined walls of the upper cone-shaped member of the mixing chamber, said upper cone-shaped member having an unobstructed extension leading to said distributor, air ports in said mixing chamber below the points where the vapor strikes the same, and means for regulating the supply of air through the air ports. 65
11. A hydrocarbon burner including in combination, a mixer having a short portion extending therefrom, a distributor mounted upon said mixer and fitting said short portion thereof, a supply valve leading into the lower portion of said mixer, and a delivery pipe having coils passing around said distributor continuously in a downward direction, said distributor having openings arranged in a spiral row, and disposed relatively to said coils, so that the oil therein is heated first gradually and finally quickly vaporized in a hot short zone in said pipe. 70
12. A hydrocarbon burner including in combination, a mixer having inclined walls, a distributor mounted upon said mixer, a supply valve located below said mixer, and having a central opening in the body portion of the valve constructed so as to throw an unbroken cone of vapor against the inclined walls of the mixer, and a delivery pipe coiled spirally about said distributor, and extending continuously in a downward direction to said supply valve, said distributor extending through said coils to a point above the same. 75
13. A hydrocarbon burner including in combination, a mixer having inclined walls, a distributor mounted on said mixer, a supply valve located below said mixer, and having a central opening therein constructed so as to throw an unbroken cone of vapor against the inclined walls of the mixer, and a delivery pipe coiled spirally about said distributor continuously in a downward direction to said supply valve, said distributor having an outwardly extending ledge provided with an annular groove for the reception of alcohol, whereby the distributor may be initially heated, said distributor extending through said coils to a point above the same. 80
14. A hydrocarbon burner including in combination, a delivering pipe, a distributor about which said pipe is coiled, said distributor having an outwardly extending ledge provided with an annular recess for the reception of alcohol, whereby said distributor and pipe may be initially heated, a supply valve, a mixer between the valve and the distributor, and a cup shaped member secured to said valve for the reception of alcohol, whereby said supply valve and mixer may be initially heated. 85
15. A hydrocarbon burner including in combination, a supply valve comprising an outer member having a receiving opening between its ends, and a delivering opening in one end thereof, the inner surface of said outer member adjacent the delivering opening being tapered away from said opening, said tapering surface in the outer member extending to the outer surface of the valve body, an inner member spaced from the outer member and extending to a point adjacent the delivering opening, said inner member being hollow, and provided with a needle in alignment with said delivering opening in the outer member, and means whereby said needle may be moved into said opening for cleaning the same, said inner member having a seat, and said needle having a shank portion fitting said seat, and means for drawing said shank portion firmly into contact with said seat. 90
16. A valve for a hydrocarbon burner, including an outer member having a delivering opening in one end thereof, an inner member spaced from said outer member and extending to a point adjacent said delivering opening, a needle located in said inner member and having an outwardly extending stem, a thumb piece on said stem, said inner member having a longitudinal slot therein, and a cam shaped outer end, a pin carried by said stem adapted to engage said slot, and said cam shaped outer end of said inner member, said needle having a shank portion, and said inner member having a seat against which said shank portion may be drawn. 95
17. A hydrocarbon burner, including in combination, a base portion, a cup member threaded into said base portion, a supply valve threaded into said cup and extending above the same, a mixer threaded onto the outer end of said supply valve, a delivery pipe connected to said supply valve at a point above said cup, a distributor mounted on the upper end of said mixer, and having perforations therein, and a delivery pipe surrounding said distributor and connected with the delivery pipe attached to said valve. 105
- In testimony whereof I affix my signature, in presence of two witnesses.
